UNITED STATES PATENT OFFICE.

HOWARD J. CLENNAN, OF AVANT, OKLAHOMA.

ATTACHMENT FOR FOUNTAIN PENS.

Application filed March 30, 1923. Serial No. 628,749.

To all whom it may concern:

Be it known that I, HOWARD J. CLENNAN, a citizen of the United States, residing at Avant, in the county of Osage and State of Oklahoma, have invented certain new and useful Improvements in an Attachment for Fountain Pens, of which the following is a specification.

This invention relates to attachments for fountain pens and more particularly to an improved construction by means of which a roll of memorandum paper may be carried in the cap of the fountain pen.

The primary object of the invention is to provide a removable attachment associated with the removable cap of the fountain pen so constructed as to fold a small roll of note paper for the purpose of taking notes and memorandums when no other paper is available.

Another object of the invention is to provide a device of this character which will be constructed so that the paper may be replenished when the original supply has been exhausted.

Other objects of the invention will appear upon consideration of the following detail description and accompanying drawing, in which:

Figure 1 is a side elevation of the pen constructed in accordance with my invention.

Figure 2 is an enlarged longitudinal section through the cap and showing my invention applied thereto.

Figure 3 is an enlarged elevation showing the end of the paper protruding from the paper holder, and

Figure 4 is a cross section of line 4—4 of Figure 2.

Referring to the drawing by numerals the fountain pen 1 is of the conventional type and is equipped with a removable protector cap 2 which, in this instance, is screw threaded in the usual manner as indicated at 3 so that it may be attached to the body of the pen. The socket end of the cap 2 which embraces the pen point is tapered to form the small flat end 4 provided with an opening to receive the shaft 5 upon which is mounted the roll of paper 6. An annular flange 7 is provided at this end of the cap 2 and the same is equipped with interior screw threads for receiving the screw threads on the paper casing 8.

The paper casing 8 is of the same size as the cap 2 with respect to its diameter and may be long enough to provide an inner compartment 9 of any desired length whereby paper of any preferred width may be included although it will be obvious that relatively narrow paper will be sufficient for the purposes of practical use of the invention. In the closed end 10 of the casing 8, a socket 11 is provided to receive the opposite end of the shaft 5 as shown to advantage in Figure 2 so that the roll of paper will be mounted to freely turn when it is to be drawn from the compartment 9. A longitudinal slot 12 is formed in the casing 8 through which the end of the paper is extended as shown in Figure 3 and the slot 12 is opened at the screw threaded end of the casing 8 so that the paper may be readily inserted when the parts are assembled.

It will be obvious from this description that when it is desired to use the paper, the pen will be removed from the cap 2 and a portion of the paper will be withdrawn through the slot 12 whereupon the pen point may be employed for making notes on the paper. The paper may be replenished by removing the casing 8 and inserting a new roll.

Claim:

An attachment of the character described comprising in combination, a fountain pen cap having one end opened and the other end closed, the closed end being provided with a tapered portion having a reduced end equipped with a perforation, said closed end of the cap also having a screw threaded flange, a removable casing having one end opened and the other end closed, the open end being adapted for screw threaded connection with the said screw threaded flange on the cap, the opposite closed end of the casing being equipped with an interior socket, a shaft adapted to have one end received in the said socket, and the other end in the said perforation, and a roll of paper adapted to be mounted upon the said shaft.

In testimony whereof, I have affixed my signature in the presence of two witnesses.

HOWARD J. CLENNAN.

Witnesses:

H. L. ROCKHOLD,
J. H. ROBBINS.
